[57] **CLAIM**

The ornamental design for a ladder inclinometer, as shown and described.

DESCRIPTION

FIG. 1 is a front perspective view of a ladder inclinometer, showing the ladder and pendulum in broken lines for illustration purposes only and forming no part of the claimed design;

FIG. 2 is a front enlarged perspective view thereof;

FIG. 3 is a front elevational view angled in one direction to the vertical thereof;

FIG. 4 is a front elevational view angled in the opposite direction from FIG. 3 thereof;

FIG. 5 is a front elevational view thereof;

FIG. 6 is a top end elevational view thereof;

FIG. 7 is a lower end elevational view thereof;

FIG. 8 is a side elevational view thereof, with the opposite side being a mirror image thereof; and,

FIG. 9 is a front elevational view of an alternate embodiment.
